EM 99767788 * 12/2013
EM 007809868-0002 * 4/2020*Primary Examiner* — Paula Allen Greene(74) *Attorney, Agent, or Firm* — Woodard, Emhardt, Henry, Reeves & Wagner, LLP(57) **CLAIM**

The ornamental design for baffles for loudspeaker, as shown and described.

DESCRIPTION

FIG. 1 is a perspective view of baffles for a loudspeaker showing my new design.

FIG. 2 is a front view thereof;

FIG. 3 is a right side view thereof;

FIG. 4 is a left side view thereof;

FIG. 5 is a top view thereof; and,

FIG. 6 is a bottom view thereof.

The broken lines illustrate portions of the environmental structure and form no part of the claimed design.
